UNITED STATES PATENT OFFICE.

JOHANN HUGENTOBLER, OF ST. GALLEN, SWITZERLAND.

THREAD-TENSION-MEASURING DEVICE.

Application filed November 28, 1921. Serial No. 518,174.

To all whom it may concern:

Be it known that I, JOHANN HUGENTOBLER, a citizen of Switzerland, and residing at St. Gallen, Switzerland, have invented certain new and useful Improvements 5 in Thread-Tension-Measuring Devices, of which the following is a specification.

The present invention has reference to certain new and useful improvements in devices for measuring the tension of the shuttle threads in embroidering machines, and it relates more particularly to a device comprising a drop member adapted to house a shuttle and a spring-influenced hand or 10 pointer acted on by the shuttle thread and traveling in front of a scale, for indicating the tension of the thread issuing from the shuttle, and I will now proceed to describe my invention in detail in connection with the 15 accompanying drawing, in which Fig. 1 is a front elevation, partly in section, and Fig. 2 a side elevation of the improved thread tension measuring device; Fig. 3 is a section on line A—B—C—D of Fig. 1; Fig. 4 is a 20 fragmental section on line E—E of Fig. 1, and Fig. 5 a partial section on line F—F of Fig. 1, looking downwardly.

The hollow base frame 1 supports the horizontal plate 2 from which rise the guide 30 pillars 3 and 4 and the standards 5 and 6. At the top these upstanding members are connected by a bridge piece 7. The pillars 3 and 4 serve as guides for the drop member 8, made up of two cylindrical weight 35 parts and a cross-piece connecting them, the cylinders being denoted by the numerals 8' and 8'' respectively, and the cross-piece by 48. On this latter is mounted a casing 10 for receiving a shuttle 9, and a stop ledge 11 40 against which the shuttle is pressed by a spring 12. To the cross-piece 48 is further secured the beveled ledge 13. The lower end of the guide pillars are extended to form discs 14 and 15 respectively, one of which, 45 for instance 14, is provided with a pin 16 of truncated cone conformation designed for cooperation with a bore 17 in the respective drop member cylinder, as clearly shown in Fig. 1. This arrangement serves to produce a "dead" stroke, that is, prevents the drop member from bouncing up again after its fall. Vertical springs 18 for retarding the drop of the drop member are interposed between the latter and the bridge member 50 7. Normally the drop member is retained in the inoperative position shown in the draw-

ing by a latch member 19 engaging below the beveled edge 13 on the drop member. This latch 19 is pivoted to the bracket 20 supported on the bridge 7 and is influenced by the 60 lever arm 21, whose one end is likewise pivoted to the bracket 20 and whose other end is linked to the draw rod 22. The lower end of this latter is pivoted to the one end of a see-saw lever 24 fulcrumed on the base plate 2 and whose other end is articulated to a press-button 23 upwardly extending through the base 1, as shown in Fig. 3. A spring 25 serves to normally keep the press button end in its uppermost position, the arrangement 65 being such that normally the latch retains the drop member in the high position. The screw pin 26, which secures the bracket 20 to the bridge 7, carries a thread tensioner 27 for mildly clampingly guiding threads of 70 various thicknesses, to prevent the thread from sluing and backlashing under the sudden operation. On the standard 6 is displaceably mounted the U-bracket 30 and a shaft 31 journaled therein carries the pointer 75 32 (Fig. 4), which latter is provided near its pointed end with a pin 33 and a plate 34 to which is secured the end of the shuttle thread 35 to be drawn out. To the U-bracket 30 is secured the plate 37 showing 80 graduation marks 36 and provided with a stop pin 38 and with a shiftable marker 40, whose raised portion 41 bears a line mark 42. The raised portion 41 is bounded by sharp edges extending parallel to the line 85 90 mark 42 for reasons to be set forth below.

On the standard 5 is rotatably clampably mounted the collar 44 from which extends a pin 43, to the free end of which a draw-spring 45 is secured. The other end of this 95 spring is attached to the lower end of the rocking pointer 32. By more or less rotatably displacing the collar 44 with its pin 43 relative to the supporting standard 5 the tension of the spring 45 can be altered to 100 take care of different shuttle-thread tensions.

The operation of the described parts is as follows: A shuttle 9 is introduced into the housing 10 of the drop member which is held in its uppermost position by the latch 105 19, the shuttle thread end is drawn out through the tensioning device 27 and is secured to the upper free end of the pointer by being wound around the pin 33 and the plate 34, the pointer 32 preferably first being swung around in the direction of arrow α (Fig. 1) to a small degree. The pointer 110

is then swung back into the initial position (Fig. 1) in contact with the stop 38, the thread now being tensioned all over its length, that is to say from the pointer end 5 to the point of issue from the shuttle. Next, by pressure on the button 23, the latch 19 is disconnected from the ledge 13 and the drop member, thus released, drops with the shuttle. Hereby, owing to the resistance of 10 spring 45, the shuttle thread 35 is drawn out, provided the resistance in the thread tension at the shuttle is not stronger than the resistance of the spring 45, in which latter case only the pointer 32 would be swung 15 to the left.

The ratio between thread tension and that of spring 45 will be indicated by the position of the pointer 32 after the fall of the drop member 8, and, since the spring tension 20 is constant, the thread tension can be read off from the position of the pointer, but it must be understood, that the pointer does not indicate the thread tension by direct reading, but only shows the difference between 25 the thread tension and the stressing of the spring acting on the pointer.

For adjusting different shuttles to the same thread tension the mark 42 is adjusted to a certain point of the scale 36 (in the 30 illustrated example to "6") and in the inserted shuttle the parts controlling the thread tension are so adjusted that the pointer 32 with its point coincides with the line mark 42 of the shiftable marker 40. The 35 sharp edges of the raised portion 41 of this marker indicate the extent of the permissible limits of error. The marker 40 is secured in the adjusted position by tightening the set screw 39.

40 What I claim is:—

1. In a device of the character set forth, in combination with a suitable support, a drop member adapted for free fall on said support, and "dead-stroke" means, for preventing 45 said drop member from bouncing-up again at the end of its descent, comprising a stationary pin of upwardly tapering conformation extending upwardly from said support in line with the drop of said drop

member, the latter presenting a respectively 50 oppositely tapering bore in its underface in axial alinement with said taper pin, adapted for jamming cooperation therewith on descent of said drop member.

2. In a device of the character set forth, 55 in combination a drop member, means thereon to receive a shuttle, means for guiding said drop member in its vertical displacement, means for retarding the fall of said drop member, and means for preventing it 60 from bouncing-up again at the end of its drop, means for normally retaining said drop member in the high position, and means for releasing the retaining means to permit the drop member to drop into the 65 low position; an indicator, comprising a scale and a pointer cooperating with said scale, spring means acting on said pointer and the latter adapted to be acted on by the thread issuing from the shuttle housed 70 by said drop member.

3. In a device of the character set forth, 75 in combination, a frame-work comprising a base, guide pillars, standards and a cross-piece, a drop member guided on said pillars and comprising tubular weight members and a bridge member connecting them, a shuttle housing on said bridge member, means for normally retaining said drop member in its 80 position and manually operable means for releasing the retaining means to permit the drop member to drop suddenly, means for producing a "dead" drop of said drop member; a combined thread guide and tensioner 85 on said frame cross-piece; an indicator mounted on one of said frame standards and comprising a scale plate having graduation marks and a stop, a U-bracket, a pointer 90 rockingly journaled in this U-bracket in front of said scale plate and adapted to register with said graduation marks, thread clamping means near the indicating, upper end of said pointer, a spring, adjustable as to its tension, acting on said pointer, and a shiftable marker on said graduated plate for 95 selective registry with said graduation marks.

JOHANN HUGENTOBLER.
